UNITED STATES PATENT OFFICE.

WILLIAM S. ELLIOTT, OF PITTSBURGH, PENNSYLVANIA.

BOILER CONTROL.

1,281,317.

Specification of Letters Patent. Patented Oct. 15, 1918.

Application filed October 17, 1914. Serial No. 867,162.

To all whom it may concern:

Be it known that I, WILLIAM S. ELLIOTT, a citizen of the United States, residing at Pittsburgh, in the county of Allegheny and State of Pennsylvania, have invented a new and useful Improvement in Boiler Controls, of which the following is a full, clear, and exact description, reference being had to the accompanying drawings, forming part 10 of this specification, in which—

Figure 1 is an elevation, largely diagrammatic, showing the application of my invention to a battery of four boilers.

Fig. 2 is an end elevation on a larger scale, 15 and also partly diagrammatic, showing the apparatus at one of the boilers.

Fig. 3 is a front elevation of one of the motors.

Fig. 4 is a sectional view of one of the 20 motors.

Fig. 5 is a plan view of the same.

Figs. 6, 7 and 8 are sections taken respectively on the lines VI—VI, VII—VII and VIII—VIII of Fig. 4.

Fig. 9 is a detail sectional view of the 25 master valve.

Fig. 10 is a sectional elevation of the casting of the master valve.

Fig. 11 is a section on the line XI of 30 Fig. 10, and

Figs. 12 and 13 are diagrammatic views illustrating the operation of the apparatus.

My invention has relation to steam boiler control; and is designed to provide means 35 of simple, efficient and reliable character whereby a group or battery of steam boilers may be automatically controlled in such a way that a substantially uniform steam pressure and substantially a constant efficiency 40 are maintained.

My invention provides apparatus of this character which may be utilized to control the boilers in various ways by suitable connections between the motive parts of the apparatus and any desired mechanism which 45 affects the generative action of the boiler.

The nature of my invention will be best understood by reference to the accompanying drawings in which I have shown a 50 preferred embodiment thereof and which will now be described, it being premised, however, that the invention is susceptible of various changes in the construction and arrangement of the parts, without depart-

ing from the spirit and scope of my invention as defined in the appended claims.

In these drawings, the numeral 2 designates the casing of a master valve which is automatically shifted from one position to another in accordance with load conditions on the boilers. This valve may obviously be of any suitable character. In the construction and arrangement shown, the casing 2 is provided with a reciprocating piston valve 3 which is arranged to be 60 shifted from one position to another to control the two ports 4 and 5 with respect to an inlet port 6. This valve is attached to a jointed rod 7 whose upper end is connected to a bar or lever 8 weighted at 9 and having a knife edge fulcrum 10 near its opposite end in a yoke 11. This yoke in turn has a knife edge fulcrum 12 upon the upper end of a rod or stem 13. This rod or stem 13 extends through a bearing box 14 into a 70 diaphragm chamber 15 where it is connected to a flexible diaphragm 16. The portion of the diaphragm chamber below the diaphragm has an inlet pipe connection 17 which leads to the steam header E, to which 80 all the boilers are shown as connected or to any other suitable point in a steam supply line leading from the boilers to be controlled.

It will readily be seen that variation in 85 the steam pressure in accordance with the changes in the load on the boilers will cause a movement of the diaphragm 16, which movement will in turn be transmitted to the bar or lever 8 and thence to the piston valve 90 3 to shift it from one position to the other, so as to connect one or the other of the ports 4 and 5 with the inlet port 6. This inlet port 6 is connected with a supply of fluid such as water. The shifting movement of 95 the valve is restricted by the stop-collars 18 on a rod 19 connected to the bar or lever 8. The casing 2 may also be provided with a drain connection 20.

The ports 5 and 4 connect, respectively, 100 with two pipe lines 21 and 22 which lead to the group or battery of boilers shown at A, B, C and D in Fig. 1.

Each boiler is provided with a motive device which operates the particular control 105 mechanism for the boiler furnace.

One of these motive devices is shown in detail in Figs. 3 to 8, inclusive. It consists

of a vertically arranged casing 23 having at its upper end an inlet port 24 provided with a manually operable shut-off valve 25. This valve 25 also controls an outlet port 25^a which leads downwardly through the wall of the casing and communicates at its lower end with a valve casing 26. The lower end of the casing 23 has an inlet port 27, provided with a control valve 28, similar to the valve 25. The valve 28 also controls the outlet port 29 leading upwardly and into a valve casing 30 which is a duplicate of the valve casing 26. The valve casing 26 has a port 31 opening into a cylinder 32 of the casing 23; and the valve casing 30 has a similar port 33 opening into said cylinder at a higher level. The communication between the outlet port 29 and the port 33 is controlled by a spring seated valve 34 in the casing 30; and the connection between the port 31 and the branch outlet port 25^a is controlled by a similar valve 36 in the casing 26. The valve 34 has its stem engaged by a lifting bar 35 whose end projects into the upper portion of the cylinder 32; and the corresponding valve in the casing 26 has a similar lifting or opening bar 36 which projects into the lower portion of the cylinder 32.

37 designates a plunger which reciprocates in the cylinder 32 and which carries a stem 38 which passes upwardly and through a stuffing box 39 at the upper end of the cylinder. The piston is provided with a stop-sleeve 40 which, by its engagement with the upper head of the cylinder, limits the movement of the piston in one direction; and also has a depending stop-rod 40^a which limits the downward movement of the piston by its engagement with the lower cylinder head 41.

The valves 25 and 28 of all the motors are normally in the open positions indicated, being provided merely for the purpose of providing means whereby the motor of any boiler can be entirely cut out of action when necessary.

The construction and arrangement of the ports at each end of the cylinder is a duplicate of that at the opposite end, thus Fig. 8 may be considered either as a section on the line VIII—VIII of Fig. 4 looking downwardly; or as a section on the line VIII—VIII^a of the same figure looking upwardly, so far as the construction is concerned.

The inlet port 24 of each motor is connected directly or indirectly to the pipe line 21; while each of the inlet ports 27 is connected directly or indirectly to the pipe line 22. With the parts in the position shown in Fig. 4, fluid from the pipe 21 will enter the upper part of the cylinder 32 through the port 24 and will pass out of said cylinder through the port 31, valve casing 26 and outlet port 25, as soon as the piston 37 has contact-

ed with the valve opening bar 36 to open the valve of the said casing 26. This is assuming that the master valve 3 has been shifted to a position in which the fluid supply is flowing through the pipe line 21. If the master valve has been shifted to the other position then fluid will enter the cylinder 32 through the port 24^a below the piston; and when the piston has been moved upwardly sufficiently far to operate the valve 75 lifting bar 35, will flow out through the ports 33 and 29. It will now be necessary to describe the connections between the motors of the several boilers. This will be best understood by reference to Figs. 12 and 13. In these figures, the motive devices are marked generally A', B', C' and D' to correspond to their respective boilers A, B, C and D. The motor D' has its inlet port 24 directly connected to pipe 21 and its outlet port 25^a connected with the inlet port 24 of the motor C'; the outlet port 25^a of C' is connected with the inlet port 24 of motor B'; the outlet port 25^a of B' is similarly connected with the inlet port 24 of A'; and the outlet port 25^a of motor A' is plugged, as indicated at 42. The bottom inlet port 27 of motor A' is directly connected to the pipe line 22 and its outlet port 29 is connected to the inlet port 27 of motor B'. The outlet port 29 of motor B' is connected to the inlet port 27 of motor C'; and the outlet port 29 of motor C' is connected to the inlet port 27 of motor D'; and the outlet port 29 of motor D' is plugged, as indicated at 42^a. From these connections it will be apparent that the motors are connected in series with respect to both pipes 21 or 22. The plugged connections 42 and 42^a may be omitted, being provided simply to make all the motors 105 alike and interchangeable.

The piston rod 38 of each piston 37 is connected to one or more controlling devices for the boiler furnace. For instance, it may be connected by a cord 43 or the like (see Fig. 2) with a weighted stack damper 44 whereby the position of the damper and the furnace draft will be varied in accordance with the extent of movement of the piston. It may also be provided with one or more 110 other connections, such as indicated at 45, and leading to other control devices. For instance, one of these connections may lead to operating mechanism for the ash pit door of the furnace; to the steam blower valve; 120 to the fan engine valve; to the valve or controller which controls the operation of the stoker valve; or, in the case of a gas fired furnace, to the valve 46 (see Fig. 1) which controls the supply of gas to the boiler furnace. 125 That is to say, the motor of each boiler may be made to operate any one or more of these different controlling mechanisms, or any other mechanism which will effect the generative action of the boiler.

The operation is as follows: Assuming that the pressure in the steam line has been decreased by an increasing demand on the boilers and the valve 3 has been shifted to 5 the position indicated in Fig. 12 to admit pressure from the pipe 6 to the pipe 21; the actuating fluid will enter the motor cylinder D' at its upper end forcing its piston 37 downwardly until the port 31 is uncovered 10 and the pilot valve 36 has been opened. This movement of the piston opens the stack damper or actuates any other boiler furnace device or devices to increase the output of the boiler. During this time of movement 15 of the piston 37, the fluid in the lower portion of the motor cylinder D' passes out through the port 27 and through the valves 28, connection 29 and valve 34 of motor C' into the upper portion of the cylinder of 20 that motor, the valve 34 at this time being open and the fluid entering the cylinder below the piston. When the pilot valve 36 of motor D' is opened, then the fluid above the piston 37 of that motor can flow through the 25 connection into the upper part of motor C'. The piston of this motor is now in turn actuated to control the corresponding boiler furnace. In the same manner the entire set of motors will be actuated successively in 30 series provided the conditions require it. That is to say, if the actuation of the motor D' does not take care of the increasing demand on the boilers, motor C' will be actuated; and if the load still increases, motor B' 35 will be actuated, and so on. In Figs. 12 and 13 it is assumed that the actuation of motors D' and C' has been sufficient to take care of the increased demand on the boilers and that motors B' and A' remain inactive, the ex- 40 haust from C' flowing idly through the cylinders of these motors and into the pipe line 22, in the manner indicated by the arrows in Fig. 12. When the demand on the boilers begins to decrease, the valve 3 is shifted 45 from the position shown in Fig. 12 to that shown in Fig. 13. Pipe line 22 is now connected with the supply connection 6 and pipe line 21 is connected to the exhaust 20. The operation is now the reverse of that before 50 described; that is to say, the incoming pressure fluid flows idly through the motors A' and B' in the manner indicated in the arrows in Fig. 13 and into the cylinder of motor C' where it raises the piston in that 55 cylinder to a point where the pilot valve 34 of that cylinder is opened. Fluid is then admitted to the cylinder of motor D' to raise the piston in that cylinder.

From the foregoing description, it will 60 be seen that the motor devices of the group or battery of boilers are operated successively in series to the extent required by changes in demand on the boilers. If the change in demand can be taken care of by 65 the cutting out or slowing down of less

than the entire group of boilers, then only the necessary number are affected. In this respect, my invention differs radically from other systems of boiler control of which I am familiar and in which all the boilers 70 of a group or battery are simultaneously affected. My invention has the advantage that the boilers not affected remain at their maximum efficiency, instead of all the boilers operating at a reduced efficiency. 75

It will also be noted that when the conditions are reversed, the motor which was the last to operate under the previous condition is the first to operate reversely under the changed condition. This is a further 80 decided advantage, inasmuch as the last boiler to be cut out or slowed down is in the best condition to be quickest restored to its maximum efficiency.

My invention, therefore, provides a system of boiler control which can be relied upon to accurately and automatically take care of widely varying demands on the battery of boilers. For instance, in the case of a peak load coming more or less suddenly 90 on or off from the boilers, the invention will operate automatically to take care of the changes in conditions. 85

It will be apparent from Figs. 12 and 13 that if desired the pilot valves 34 and 36 95 can be omitted, and the pistons 37 made to act as their own valves. I prefer, however, to employ these pilot valves as they provide positive means for controlling the operation of successive cylinders, notwithstanding 100 considerable wear on the pistons which might result in leakage and failure of accurate operation.

It will be readily understood that I do not wish to limit myself to the particular 105 valve and motor construction and arrangement which I have herein shown and described, as these can obviously be widely varied without departing from the spirit and scope of my invention as set forth in 110 the appended claims. Thus any suitable type of motor may be employed, with means whereby it will operate the furnace regulators in reverse conditions, the master controller may be widely varied, and other 115 changes may be made.

It will also be understood that while I have shown my invention applied to a group or battery of four boilers it can be applied to a larger or smaller number as 120 may be necessary in any particular case.

I claim:

1. Apparatus for controlling a plurality of boilers, comprising regulating means for the furnace of each boiler, a motive device 125 operatively connected to the regulating means, and means controlled by the combined boiler pressure for operating the motive devices successively in a predetermined order to the extent required by the 130

changes in such pressure, there being also means whereby the number of motive devices which will be successively operated under any given change in such pressure is dependent upon the extent of such change.

2. Apparatus for controlling a plurality of boilers, comprising regulating means for each boiler furnace, a motive device operatively connected to the regulating means of each furnace, and means controlled by the boiler pressure for operating the motive devices, said devices having controlling means for effecting the successive operation of the motive devices in a predetermined order to the extent required by the changes in such pressure, said motive devices and controlling means having means whereby the number of motive devices which will be successively operated under any given change in such pressure is dependent upon and in direct relation to the extent of such changes.

3. Apparatus for controlling a plurality of boilers, comprising regulating means for each boiler furnace, a motive device operatively connected to the regulating means of each furnace, means controlled by the boiler pressure for operating the motive devices successively in a predetermined order to the extent required by changes in such pressure, and controlling means whereby the motive devices operate successively in reverse order under opposite conditions of pressure, said motive devices and controlling means having means whereby the number of motive devices which will be successively operated under any given change in such pressure is dependent upon and in direct relation to the extent of such change.

4. Apparatus for controlling a plurality of boilers, comprising regulating means for the furnace of each boiler, a motive device operatively connected to each regulating means, a master controller for controlling the direction of operation of the motive devices, and other controlling means for the motive devices for successively operating them in a predetermined order, said motive devices and controlling means having means whereby the number of motive devices which will be successively operated under any given change in such pressure is dependent upon and in direct relation to the extent of such change.

5. Apparatus for controlling a plurality of boilers, comprising regulating means for the furnace of each boiler, a motive device operatively connected to each regulating means to operate the same in reverse direction, a master controller for controlling the direction of operation of said regulating means, and other controlling means for the motive devices for successively operating them in series, said controlling means effecting a reverse order of operation of the regulating means in opposite directions.

6. Apparatus of the character described, comprising separate regulating means for each of a plurality of boiler furnaces, a fluid operating motor operatively connected to each regulating means, a fluid supply system in which the motors are connected in series, and a master valve for said supply system controlled by the boiler pressure.

7. Apparatus of the character described, comprising separate regulating means for each of a plurality of boiler furnaces, a fluid actuated motor operatively connected to each regulating means, a fluid supply system in which the motors are connected in series, and a master valve for said supply system controlled by the boiler pressure, together with means whereby any motor may be cut out of operation without affecting the remaining motors.

8. Apparatus of the character described, comprising separate regulating means for each of a plurality of boiler furnaces, a fluid operating motor operatively connected to each regulating means, a fluid supply system in which the motors are connected in series, and a master valve for said supply system controlled by the boiler pressure, each of said motors having self controlled pilot valves.

9. Apparatus of the character described, comprising separate regulating means for each of a plurality of boiler furnaces, a fluid operating motor operatively connected to each regulating means, a fluid supply system in which the motors are connected in series, and a master valve for said supply system controlled by the boiler pressure, the series connections between the cylinders of the motors having pilot valves, and means for causing the pistons of the motors to automatically control said valves.

10. The combination with a plurality of boilers and their furnaces, of furnace regulating devices operative by changes in the pressure of the combined steam output of the boilers to successively affect their generating action in a predetermined order, said devices having means whereby the number of boilers so affected by any such change is dependent upon the extent of such change.

11. The combination with a plurality of boilers and their furnaces, of a regulating device for affecting the steam generating action of each of a number of said boilers independently of all the other boilers, means for utilizing changes in the combined steam pressure of all the boilers to operate said regulating devices successively in a predetermined order, and means whereby the number of regulating devices operated by reason of any such change depends upon the extent of such change.

12. The combination with a plurality of boilers and their furnaces, of a regulating device for affecting the steam generating

action of each of a number of said boilers independently of all the other boilers, means for utilizing changes in the combined steam pressure of all the boilers to operate said regulating devices, and means whereby the number of regulating devices operated by reason of any such change depends upon the extent of such change, and also whereby the last regulating device to operate under 10 a change of pressure in one direction will be the first to operate under a reverse change.

13. The combination with a plurality of boilers and boiler furnaces, of furnace controlling devices, and means whereby any change in the load on the system supported by said boilers operates so many only of the said devices in a predetermined order as is necessary to decrease or increase the 20 steam supply sufficiently to compensate for that particular change.

14. The combination with a plurality of boilers and boiler furnaces, of furnace controlling devices operated successively in a 25 predetermined order by changes in the load on the system supplied by said boilers, and means whereby the number of regulators which will operate upon any given change in the load is dependent upon the extent of 30 such change.

15. The combination with a plurality of boilers and boiler furnaces, of furnace controlling devices operated successively in a predetermined order by changes in the load 35 on the system supplied by said boilers, and means whereby the regulating devices of different furnaces will be operated successively as such load decreases or increases.

16. The combination with a plurality of 40 boilers and boiler furnaces, of furnace controlling devices operated successively in a predetermined order by changes in the load on the system supplied by said boilers, and means whereby each successive regulating 45 device requires a greater change in such load than the preceding one to effect its operation.

17. The combination with a plurality of 50 boilers and boiler furnaces, of furnace controlling devices operated successively in a predetermined order by changes in the load on the system supplied by said boilers, and means whereby some of the regulating devices will operate under a relatively small 55 change in such load, while others require a greater change to effect their operation.

18. The combination with a plurality of boilers and their furnaces, of a regulating device for each furnace for affecting its fuel consumption, a master controller, means controlled by changes in the load on the system supplied by said boilers for shifting said master controller, and means governed by the master controller for actuating said regulating devices, and means whereby each 60 succeeding regulating device cannot operate until a preceding device or devices has been operated.

19. The combination with a plurality of boilers and boiler furnaces, of furnace controlling devices operated by changes in the load on the system supplied by said boilers, and means whereby each succeeding regulating device cannot operate until all the preceding ones have been operated.

20. The combination of a plurality of steam boilers, a furnace for each boiler, a steam receiver common to all of the boilers, a combustion-controlling device for each boiler, and pressure responsive means in 80 communication with the steam receiver and adapted to operate the said combustion-controlling devices successively and in a predetermined order according to variations of pressure in the steam receiver.

21. The combination with a plurality of regulators for controlling boiler furnace combustion and thereby steam generation, of means responsive to the pressure of the generated steam and adapted to operate the 90 said combustion regulators successively and in a predetermined order according to variations in such steam pressure.

22. The combination with a plurality of regulators for controlling combustion and 95 thereby steam generation, of actuating devices for said regulators controlled by variations in the pressure of the generated steam, said devices having means whereby the several regulators will be operated successively 100 in a predetermined order, the number of the regulators which will be operated under any given variation in steam pressure being dependent upon the extent of such variation.

In testimony whereof, I have hereunto set 105 my hand.

WILLIAM S. ELLIOTT.
